COLLAPSIBLE RECEPTACLE

Charles A. Van Wagner, Winston-Salem, and
Clyde M. Andrews, Greensboro, N. C.

Application February 17, 1944, Serial No. 522,688

1 Claim. (Cl. 217—12)

This invention relates to a shipping box, crate, coop, or container, and the like which is of a collapsible nature, and which can be erected and packed full of goods and then can be secured against opening during shipment, and when the crade, box, container, and the like reaches its destination, it can be opened and emptied, and the walls, top and bottom can be collapsed to occupy a very small space, so that the collapsed shipping container can be returned to the shipper, occupying a very small amount of space in the return shipment.

It is an object of this invention to provide a collapsible shipping box having a bottom, top, and four side walls with the contacting portions between all portions of the box having tongue and groove connections whereby when the box is in assembled position and secured against opening, and the lid is secured against movement, the box will be held in rigid closed position, so as to be used as a shipping box and when it is emptied, the parts can be stacked one upon the other and bound together by any suitable means such as an iron strap passing around the same, and shipped back to destination, or in one form of the invention where the portions are shown hingedly connected together, it can be folded into a compact position whereby the crates can be packed in a car or truck and returned to the shipper, without binding the parts together.

It is another object of this invention to provide a collapsible box or crate or shipping case having a bottom with a tongue disposed along and in close proximity to the ends and sides of the bottom member and having end walls and side walls provided with grooves in their upper and lower edges and having a lid portion having tongues disposed along its side and end edges, the tongues on the bottom and lid portions being adapted to fit into the grooves in the lower and upper edges of the side and end walls so that when the end and side walls are moved to raised position, and the lid is placed in position on the top edges of the end and side walls, all portions of the box will be supported by each other, and when the lid is confined in position, a sturdy shipping box will be provided which will stand all stresses and strains from the inside and the outside, and which when it is emptied, is adapted to be collapsed and shipped back to the shipper for use over and over again.

Some of the objects of the invention having been stated, other objects will appear as the description proceeds, when taken in connection with the accompanying drawings, in which:

Figure 1 is an isometric view of the box or crate;

Figure 2 is an isometric view similar to Figure 1, but showing the reverse sides thereof;

Figure 3 is a top plan view of the box in opened

position and looking at the interior surfaces of the box or crate;

Figure 4 is a vertical sectional view taken transversely through the box or crate as shown in Figure 2;

Figure 5 is a horizontal sectional view taken through the box or crate as shown in Figure 2;

Figure 6 is an enlarged detail view of one corner of the box or crate, such as the upper right-hand corner of Figure 4, showing a modified form of tongue and groove;

Figure 7 is a view similar to Figure 6, but showing another modified form of tongue and groove arrangement;

Figure 8 is a top plan view of the box or crate with the top removed;

Figure 9 is an isometric view of the box or crate similar to Figure 1 but without any hinges and having a strap iron member secured therearound for holding the lid in closed position;

Figure 10 is an end view of the box or crate of the type shown in Figures 1-8 in collapsed position and ready for reshipment.

Referring more specifically to the drawings, A represents the bottom of the box, while B and C represent the two sides, D the top or lid, and E and F the end positions. All of these parts of the box comprise a suitable framework and over the interior surface of the top and bottom is secured a sheet member such as ply wood, or a composition material, indicated by reference character 10. The sides B and C have the sheets 11 secured over the interior surfaces of the same, and the end portions E and F have sheets 14. The bottom and top portions A and D have along each side thereof tongues 16 and 17 and along the end portions thereof tongues 18 and 19. The side portions B and C have along the ends thereof grooves 20 and 21 and also have grooves 22 and 23 along the bottom and top edges. The end portions E and F have along the top edge thereof grooves 25 and along the bottom edge thereof grooves 26.

If desired, the side walls and end walls can be secured in a hinged relation by means of flexible straps 30 which may be made of canvas belting, leather, or any other suitable pliable material, and these are secured near their ends to the respective portions of the box as at 31 by any suitable means such as tacks or nails, although they could be suitable screws if desired.

The end portions E and F have tongues 27 and 28 on their inside surfaces adjacent each side thereof adapted to fit into grooves 20 in one end of sides B and C and grooves 21 in the other ends of sides B and C.

For holding the box with the sides walls and end walls in erected or vertical position while filling the box or crate full of goods and before the lid portion is placed thereon, suitable clamps 35 having inturned ends 36 may be secured as

shown in Figure 8 for holding the box or crate in erected position. After the box or crate is filled with merchandise, and the lid D is placed in closed position, any suitable means may be employed for holding the box in assembled position and holding the lid in firm position on top of the side and end walls by means of passing therearound a strap 40 such as a steel strap as used in baling cloth, cotton, and the like, and a suitable metal portion 41 may be crimped therearound to hold the strap 40 in a taut position around the box.

Instead of having the rounded or convex tongues and the concave grooves made on the arc of a circle as shown in Figure 4, for example, 15 the tongues may be made in other shapes, such as in Figure 6 where the tongue 16a is shown of angular formation, and the groove 23a is shown of like concave formation to receive the tongue 16a or, if desired, the tongue 16b can be formed 20 as shown in Figure 7 with its conforming groove 23b provided for receiving the tongue 16b.

In assembling the box, crate, receptacle, or the like, the side walls B and C are raised upwardly and inwardly from the position shown in Figure 3, and the grooves 22 fit down over the tongues 16 and 17. Then the end walls are raised upwardly and inwardly on their hinges, if hinges are provided, and the tongues 27 and 28 are fitted into the grooves 20 and 21 in the ends of the 25 side walls B and C and the tongues 18 and 19 fit into the grooves 26 in the bottom edge of end portions E and F. Then the lid portion is placed in position with the tongues 18 and 19 fitting into the grooves 25 on the top surfaces of the end 30 portion, and the tongues 17 and 16 fit in the grooves 23 in the top surfaces of the side portions B and C. This causes all portions of the box to be firmly locked together as long as the lid D is held firmly in position, and this can be accomplished by any suitable means such as the strap 40 as shown in Figure 9.

It is not necessary to have the hinges 30 connecting the various portions of the box or receptacle together as shown in Figure 3. This is merely to keep the parts from becoming separated from each other, but if desired, these hinges can be dispensed with as shown in Figure 9 where the box can be assembled and held in position by the clamp members 35 while being filled with merchandise and then the lid portion D can be placed in position and the straps 40 passed around the entire box or crate and when the box or crate reaches its destination, the band 40 can be parted if desired, but if the merchandise contained therein is of a nature which might not retain the shape in which it is packed, the clamp or braces 35 could be placed in position before the strap 40 is severed, and then when the box or crate is emptied, the sides, top, bottom, and end members can be packed flat one upon top of the other and bound together by any suitable means such as a strap member 40 for reshipment back to the shipper.

Figure 10 shows a convenient way of reshipping the collapsed container which has its portions hingedly connected together back to the shipper wherein the reference characters fully indicate how the box can be folded for reshipment. One convenient way of doing this is to 70 invert the box from the position shown in Figure 3 with the hinges nearest the observer, and then

move the end portions E and F over on top of the bottom portion A, and then fold the side portion B over the folded end portions, and then the top D can be folded backwardly over the other side wall C and the container can very easily be shipped back to the shipper in this form by packing a number of the same in trucks or a boxcar for reshipment back to the sender.

Although we have shown the tongues 16, 17, 22, 23, 27, and 28 and the grooves 20, 21, 25, and 26 formed integrally with the walls, top, and bottom, it is evident that plain surfaced top, bottom, and walls can be employed and strips of material having the desired tongue or groove formed therein can be suitably secured to the parts of the container instead of forming the tongues and grooves from the material of the walls, top, and bottom, and these strips having the tongues and grooves can be of any suitable material such as metal, wood, plastic, or any convenient and desired material.

Although we have shown the container as having a lid, it is evident that the lid can be dispensed with such as in bottle crates and the like which usually have no lid, and a suitable band can be passed around the end and side walls to confine the container in assembled position without employing a lid. Or, if desired, a band can be passed around the erected container in a manner similar to that shown in Figure 9, but with the lid omitted, and this will hold the box, minus the lid, in erected position when it is used as a bottle crate, for example, where no lid is required.

In the drawings and specification, there has been set forth a preferred embodiment of the invention, and although specific terms are employed, they are used in a generic and descriptive sense only and not for purposes of limitation, the scope of the invention being defined in the claim.

We claim:

A collapsible container having a bottom, four walls, and a top, each of the walls and the bottom and top comprising a sheet member of flat material such as plywood and each sheet having relatively thick strips of material secured on the exterior of the sheets adjacent the four edges thereof and projecting outwardly beyond the edges of the sheet member and joined to each other at their ends, the strips forming a part of the bottom having upwardly projecting tongues extending longitudinally of the strips, the top and bottom strips associated with each of the walls having longitudinally extending grooves therein, the side strips of opposed walls having tongues extending longitudinally of the inner surface thereof and the side strips of the other two walls having longitudinally extending grooves in their outer surfaces, the strips associated with the top member having longitudinally extending tongues on their lower surfaces, whereby when the container is assembled the grooves in the lower edges of the walls will fit over the tongues along the four edges of the bottom member and the tongues in a pair of opposed walls will fit into the grooves in the ends of the other two walls and the tongues on the top will fit into the grooves in the top edges of the four walls.
